UNITED STATES PATENT OFFICE.

WILLIAM S. PUGSLEY, OF LONDON, CANADA.

WIRE-FENCE MACHINE.

SPECIFICATION forming part of Letters Patent No. 738,356, dated September 8, 1903.

Application filed December 24, 1902, Serial No. 136,510. (No model.)

To all whom it may concern:

Be it known that I, WILLIAM S. PUGSLEY, a subject of the King of Great Britain, and a resident of the city of London, in the county 5 of Middlesex, in the Province of Ontario, Canada, have invented a certain new and useful Wire-Fence Machine, of which the following is a specification.

This invention relates to a machine for 10 weaving the vertical stay-wires with the horizontal wires of wire fences; and it consists of the improved construction and novel combination of parts, as will be hereinafter first fully set forth and described, and then pointed out 15 in the claims.

The object is to provide a simple, strong, durable, and efficient machine that will weave two vertical stay-wires with the longitudinal fence-wires at one operation and at the same 20 time a machine that will be easy to operate.

Reference is had to the accompanying drawings, wherein—

Figure 1 is a side view of a wire-fence machine embodying my invention. In this view 25 the spacing-bar and hook secured thereto are shown in dotted lines. Fig. 2 is an end view of Fig. 1. In this view the beveled gear-wheel is partly cut away. Fig. 3 is a plan view of the weaving apparatus. In this view the main 30 beveled gear-wheel is partly cut away. Fig. 4 is a detail front view of the rotating frame and attachments. Fig. 5 is an end view looking at the pinion end of Fig. 4. Fig. 6 is a view of the end opposite to the pinion end of 35 Fig. 4. Fig. 7 is a detail side and front view of one of the brackets which support the hubs of the rotating frame. Fig. 8 is a detail end view of one of the spacing-clips and connections. Fig. 9 is a side view of the clip shown 40 in Fig. 8. Fig. 10 is a detail plan and end view of one of the slides and attachment on which the machine is pivoted.

In the accompanying drawings the numeral 1 designates the main frame provided with a 45 spindle 2, secured to the rear side, with an inclined flange 1^a and locking-notch 3 on the upper side, and with arms 5 and bolt-holes 7 at the two opposite ends.

8 designates a beveled gear-wheel held in 50 place supported by and turning perfectly free on the spindle 2, and said gear-wheel is provided with a square crank-pin 9.

10 designates a crank which engages with the crank-pin 9, and said crank is provided with a handle 11 and flanges 12.

55

13 designates a spring-dog which is pivotally mounted on the crank 10. The inner end of which dog 13, when in its normal position, is adapted to engage with the locking-notch 3.

14 designates brackets secured to and near 60 the opposite ends of the frame 1, as shown in Fig. 1, in which brackets the circular bearing-sockets 15 (shown particularly in Fig. 7) are formed, and 16 is an opening, one of which is formed in one side of each of said 65 brackets, which opening extends inward from one edge to and communicates with the circular bearing-socket 15.

17 designates a beveled gear-pinion adapted to engage with the beveled gear-wheel 8, and 70 18 designates a head, and said head and said pinion are connected together by the bars 20 and are each formed with a hub 19, (shown particularly in Fig. 4,) and said hubs are fitted to, supported by, and rotate perfectly free 75 in the circular bearing-sockets 15 in the brackets 14. 21 designates a slot, one of which is formed in said pinion 17 and head 18 and in the hubs 19, adjacent thereto, said slot extending from one edge inward to a point beyond the center, and at their inner ends said slots 21 are formed with recesses 24, which extend laterally in opposite directions from said slot. 22 designates a pair of flanges formed on the outer ends of each of said hubs 80 85 19, one on each side of the slot 21.

23 designates pins, one of which is secured in the flanges 22 at the outer end of each hub.

25 designates wire loops or spools, one of which is secured to the adjacent side of said 90 pinion 17 and head 18, on which loop 25 the coil of wire 26 is placed from which the vertical stay-wires are formed.

29 is a clasp secured to the frame 1, which extends over on the back of the beveled gear-wheel 8 at the point where the beveled pinion 17 engages therewith to prevent said pinion and wheel from spreading apart and the teeth of one from slipping over or riding on the teeth of the other.

30 and 31 designate spacing-standards connected together by the cross-bars 28, and each of said spacing-standards is provided on one side with the lateral flanges 32, and 32^a repre-

100

sents lateral flanges formed on the opposite side of the spacing-standard 31 to that on which the flanges 32 are formed, as shown in Fig. 8.

5 33 designates a spacing-bar provided on one side with the laterally-projecting flanges 33^a, which spacing-bar is pivotally secured to the brackets 34, and the latter are secured to the spacing-standard 30.

10 35 designates a hook pivotally secured to the spacing-bar 33, and said hook is provided with a notch 36, which engages with the adjacent horizontal fence-wire 37 to hold the spacing-standard 30 against the horizontal fence-wires 37.

15 39 designate spring-clips provided with the flanges 40 and the latter with the inturned shoulders 40^a, which shoulders engage with the flanges 32^a of the spacing-standard 31 or 20 with the flanges 33^a of the spacing-bar 33, as shown in Fig. 8.

25 41 designates a notched and tapered gib-key which extends through a lateral opening 42 in the spacing-clips 39, between said spacing-standard and said spacing-clip, to firmly hold the latter at the position to which it is adjusted on said spacing-standards.

30 43 designates slides provided with the flanges 44 and the latter with the inturned shoulders 45, which shoulders engage with the flanges 32 of the spacing-standards 30 and 31, as shown in Fig. 10, and each of said spacing-standards 30 and 31 is provided with one of said slides. 46 designates pivot-bolts, 35 one of which is held in place and supported by each of said slides 43, which bolts are fitted to the holes 7 in the opposite ends of the frame 1, on which bolts said frame 1 is pivotally supported.

40 The operation is as follows: Two coils of wire 26 are placed on the loops or spools 25, as shown in Fig. 1. In this view short coils of wire only are shown; but said coils of wire may be of different diameter and one telescope within the other, and when so constructed each coil could extend the full length of the rotating frame. After the coils of wire 26 are placed on the loops or spools 25 one of the ends of the wire of one wire coil is threaded through the slot 21 between the pin 23 and the adjacent portion of the pinion 17 and hub 19, as shown in Fig. 5, and the end of the wire of the other wire coil is threaded through the slot 21 between the pin 23 and 50 adjacent portion of the head 18 and hub 19, as shown in Fig. 6. These ends of the wire of the wire coils 26 are then bent around, and thus held in engagement with the arms 5 of the frame 1. The weaving apparatus is then 55 adjusted on the spacing-standards until the arms 5 rest on the upper horizontal fence-wire 37. The weaving apparatus is then further adjusted toward said wire 37 until the latter abuts against the pins 23, and in order 60 to permit this adjustment the slots 21 in the head and pinion must register with the openings 16 in the brackets 14, which they do

when the dog 13 engages with the locking-notch 3. The crank 10 is then grasped and the spring-dog 13 compressed to release it 70 from the locking-notch 3, when the crank 10 and beveled gear-wheel 8 is rotated once, and just as the dog 13 clears the notch 3 the compression is removed from said dog, so that when said dog comes opposite the notch 3 75 again it is automatically adjusted into said notch, which prevents the further rotation of the weaving apparatus until compression is again applied to said dog to release it from said locking-notch 3. While the beveled gear-wheel 8 has been turning once, the beveled gear-pinion 17 and rotating frame, of which it is a part, has been rotated three times, and the ends of the wire of the wire coils 26 being held between the pins 23 and adjacent 80 portion of the pinion 17 and head 18, as before described, these ends of the wire of said wire coils are each twisted three times around the horizontal fence-wire 37, and as the ends of the wire of said wire coils 26, in engagement with the arms 5, are securely held in contact with said arms the wire to form these coils, which are twisted around the horizontal fence-wire 37, is drawn from the wire coils 26 on the loop or spool 25. The 85 weaving apparatus is then adjusted back from the spacing-bars and horizontal fence-wires to the position shown in Fig. 2, and as these ends of the wire of said wire-coils are now secured to one of the horizontal fence-wires as the weaving apparatus is adjusted to the position shown in Fig. 2 sufficient wire from both coils is drawn from them to form the portion of the vertical stay-wire between two horizontal fence-wires and to permit the arms 90 of the weaving apparatus to lower, so that they will engage with the next horizontal fence-wire, as before described, when the operation before described is repeated, and as the arms 5 are adjusted to the position 95 shown in Fig. 2 they slip out of the portion of the wire bent around them, and thus permit the weaving apparatus to lower perfectly free to the next horizontal fence-wire. To support the frame 1, carrying the weaving 100 mechanism on the spacing-standards 30 and 31, the bolt 46 is projected through the bolt-hole 7 in the frame 1, as before described, and the inturned shoulders 45 of said slides 105 43 are engaged with the flanges 32 of said standards at one end, as shown in Fig. 10, after which, by grasping the crank 10, said frame, slides, and weaving apparatus may be adjusted upward or downward to any point desired on said standards.

110 The spacing-clips 39 are engaged with the flanges 32^a of the spacing-standard 31, as shown in Fig. 8, and with the flanges 33^a of the spacing-bar 33 in the same manner, and after said spacing-clips have been adjusted to 115 the desired position, which is governed by the distance apart the horizontal fence-wires 37 are required to be, they are firmly locked and held in said position by driving in the tapered 120

gib-keys 41. The spacing-standard 31 is first secured to the horizontal fence-wires 37 by removing the pins 39^a from the spacing-clips 39 and then placing said spacing-standard 31 adjacent to the fence-wires and a horizontal fence-wire in each spacing-clip, after which, by inserting the pins 39^a in said clips, said fence-wires 37 are firmly held in said clips. The spacing-clips 39 on the pivot-bar 33 have no pins 39^a. These pins are not necessary in these clips, because when the spacing-bar 33 is adjusted to the position shown by solid line in Fig. 2 the adjacent side of the spacing-standard 30 prevents said horizontal fence-wires from accidentally disengaging from said clips. When so placed, said horizontal fence-wires 37 are held spaced apart while the stay-wires are being woven around them, and after the horizontal fence-wires have been placed in the clips 39 the hook 35 is engaged with the adjacent horizontal fence-wire to prevent the spacing-standard 30 from moving away from the adjacent fence-wires. In addition to this the horizontal fence-wires extend between the spacing-standard 30 and spacing-bar 33.

After the machine has woven the two vertical stay-wires with the lowest horizontal wire of the fence the stay-wires are cut at some convenient point between the lowest fence-wire and the wire coil 26, after which the spacing-standards and weaving apparatus pivoted thereon are moved longitudinally to the point where it is required to weave additional stay-wires with the horizontal fence-wires.

In using this invention all that the operator has to do after weaving the vertical stay-wire around the top horizontal fence-wire is to adjust the frame and attachments to the position shown in Fig. 2 to disengage the arms 5 from the preceding horizontal fence-wire and to draw sufficient wire from the coil 26 to extend from one horizontal fence-wire to the other, then to adjust the machine until the arms 5 rest on the horizontal fence-wire, and then insert the latter in the openings 16 and slots 21, as herein described, make one revolution of the gear-wheel 8, and so on. As a result, a simple, strong, durable, inexpensive, and efficient wire-fence machine is provided, and one that will readily and easily weave two vertical stay-wires with the horizontal fence-wire at one operation.

Having thus described my invention, I claim—

1. In a machine of the class described, a frame, provided with a spindle and an inclined flange, a locking-notch formed in said frame, a beveled gear-wheel rotatably mounted on said spindle, a crank for operating said beveled gear-wheel, and a spring-dog pivotally mounted on said crank and adapted to engage with said inclined flange and said locking-notch in said frame, in combination with a wire-carrying rotatable frame provided with a beveled gear-pinion, adapted to engage with

said beveled gear-wheel, and means for supporting said rotatable frame, substantially as and for the purpose set forth. 70

2. In a machine of the class described, a wire-carrying rotatable frame, provided with hubs, slots formed in the opposite ends of said frame and said hubs, flanges on the ends of said hubs, and a pin secured in said flanges and extending across said slots, in combination with brackets, circular bearing-sockets formed in said brackets, in which said hubs are supported, an opening formed in one side of each of said brackets which communicates with the slots in the ends of said rotatable frame, and means for supporting said brackets, substantially as and for the purpose set forth. 75

3. In a machine of the class described, a frame provided with outwardly-projecting arms, brackets supported by said frame, a circular bearing-socket formed in each of said brackets and an opening formed in one side of each of said brackets which communicates with the circular bearing-socket therein, in connection with a rotating frame consisting of heads connected together by said connecting-bars, hubs on the outer ends of said heads, slots in the ends of said frame and said hubs, flanges on the ends of said hubs, pins secured in said flanges, and wire-supporting loops or spools secured to the adjacent sides of the heads of said rotatable frame, substantially as and for the purpose set forth. 90 100

4. In a machine of the class described, a spacing-clip, flanges on said clip, and inturned shoulders on said flanges, a pin secured in said clip, and a notched and tapered gib-key, in combination with a spacing-standard, provided with laterally-projecting flanges with which the inturned shoulders on said clip engage, substantially as and for the purpose set forth. 105

5. In a machine of the class described, a spacing-clip, flanges on said clip, inturned shoulders on said flanges, and a notched and tapered gib-key, in combination with a spacing-bar—provided with laterally-projecting flanges with which the inturned shoulders on the clip engage, and a spacing-standard, to which said spacing-bar is pivotally secured, substantially as and for the purpose set forth. 110 115

6. In a machine of the class described, slides, flanges on said slides, inturned shoulders on said flanges, and a frame carrying a wire-weaving apparatus pivotally secured to said slides, in combination with spacing-standards provided with laterally-projecting flanges, substantially as and for the purpose set forth. 120 125

7. In a machine of the class described, a frame provided with outwardly-projecting arms, brackets supported by said frame and having circular bearing-sockets formed therein, a rotating frame provided with hubs, which are fitted to and inserted in said circular bearing-sockets in said brackets, slots in the ends of said frame and said hubs, 130

flanges on the ends of said hubs, pins supported in said flanges, and loops or spools secured to the adjacent faces of the heads of said rotating frame for supporting coils of 5 wire, in combination with spacing-standards, slides adjustable thereon, to which slides the main frame is pivotally secured, a spacing-bar pivotally secured to one of said spacing-standards, and spacing-clips secured to the

other spacing-standard and said spacing-bar, to substantially as and for the purpose set forth.

In testimony whereof I have signed in the presence of the two undersigned witnesses.

WILLIAM S. PUGSLEY.
